BALL-POINTED PEN

By D. Morris, Baldwin, N. Y., assignor to Universal Fountain Pen & Pencil Co., Inc., New York, N. Y., a corporation of New York

Application April 27, 1948, Serial No. 23,479

2 Claims. (Cl. 120—42.4)

1

This invention relates to ball-pointed fountain pens. Pens of this type are equipped with a small ball rotatably mounted in a socket at the tip of the pen to which viscous ink is fed through a conduit of small bore from an ink reservoir in the barrel of the pen. The writer causes the ball to rotate in its socket and roll over the surface written upon, thus transferring ink from the socket to the paper. It often happens, particularly after long periods of disuse, that a bubble of air becomes lodged in the feed conduit, or the ink in the socket becomes dry, or the normal flow of ink is otherwise arrested so that the pen will not write, or, in any event, will not write freely and instantly.

In each of my copending applications, Serial No. 757,847, filed June 28, 1947, and Serial No. 783,523, filed November 1, 1947, I have disclosed and claimed a small air compressor mounted on such a pen and communicating with the ink reservoir. Air is compressed by means of a thumb-actuated plunger slidably mounted within a cylinder from which the compressed air enters the ink reservoir. In my copending application, Serial No. 791,562, filed December 13, 1947, now Patent Number 2,500,998, dated March 21, 1950, I have disclosed and claimed a modified form of air compressor. In each instance a vent is provided for relieving the pressure within the reservoir as soon as the flow of ink has been reestablished.

I have discovered that better results are obtained by maintaining the slightly increased pressure within the reservoir. With a properly made compressor the small increment of pressure obtained may be held for a long time, during which the pen writes freely and instantly, and when the pressure eventually drops to atmospheric, so that the pen does not write well, or if for any reason the ink does not flow, the compressor is again operated to rebuild the pressure. It is, therefore, the object of the present invention to provide a ball-pointed pen with means for slightly compressing the air above the ink in the ink reservoir, for maintaining that pressure, and for replenishing it from time to time.

In the accompanying drawing, in which I have shown a preferred embodiment of my invention,

Figure 1 is a longitudinal section through a ball-pointed pen of my invention showing the compressor as it appears at the end of the compression stroke, and

Figure 2 is a view similar to Figure 1 but showing the compressor at the end of the pressure releasing stroke.

The pen illustrated in this drawing comprises a 55 of the cylinder and the reservoir, and through

metal tube constituting an ink reservoir 1 terminating in a conical tip 2 in the end of which is a writing ball 3 rotatably mounted within a socket. The ink passes from the reservoir to the ball through a fine feed conduit, not shown. These parts, which constitute the elements of the pen proper, are mounted within and upon a plastic barrel or housing 4 terminating at its forward end in a conical sleeve 5. The parts just described are common elements of a ball-pointed pen and, of themselves, form no part of my invention.

Mounted upon the upper end of the ink reservoir tube is a plug 6 having a fine central bore 7. Lower down in the tube is a smaller plug 8 likewise provided with a fine central bore 9 and press-fitted within the tube, the chamber 10 between the plugs 6 and 8 constituting an ink trap.

Slidably mounted upon the plug 6 is a plunger cylinder 11 provided in its sidewall with an air vent 12 and having inwardly bent tongues 13 (only one shown) for preventing accidental removal. Within the cylinder 11 and overlying the upper end of the plug 6 is a rubber or neoprene washer 14 of slightly larger diameter than the plug and making air-tight, frictional engagement with the walls of the cylinder and with the end of the plug. This washer is provided with a central bore 15. Overlying the washer 14 is a brass washer 16 also provided with a central bore 18 and lying within the cylinder 11 between the washer 16 and the end of the cylinder is a compression coil spring 19.

Adjustably screwed within the upper end of the barrel 4 is a plug 20, having a head 21 and a threaded boss 22, an annular shoulder 23 being defined by the underface of the head and the boss. The inner end of the boss engages the outer end of the cylinder 11; thus when the plug is screwed inward the cylinder 11 is pressed downward and the coil spring 19 compressed, the limiting position being reached when the shoulder 23 abuts the outer rim of the barrel, as shown in Figure 1. When the plug is unscrewed, the cylinder 11 moves outward under the compulsion of the spring until the tongues 13 engage the projecting shoulder on the underface of the plug 6, as shown in Figure 2. It will be noted that when the cylinder is in its innermost position, as shown in Figure 1, the air vent 12 is out of communication with the interior of the cylinder 11 and the reservoir 10, but that when the cylinder is in its outermost position, as shown in Figure 2, the air vent 12 is in communication with the interior

an opening 24 in the barrel, places them in communication with the atmosphere.

The pen just described operates as follows: Assuming the parts to be in the position shown in Figure 2, the user screws the plug 20 inward. This movement forces the cylinder 11 inward, compressing the spring 19 and the air within the chamber 10 of the ink reservoir. When the plug is screwed in to its limiting position, the parts assume the position shown in Figure 1 with the air vent 12 out of communication with the reservoir (either because the air vent is below the washer 14 or opposite it) and the pen is in normal writing condition with the ink under a slightly increased pressure. This slight increment in pressure causes the ink to flow freely to the ball and enables the pen to write instantly when the ball is applied to paper. Gradually, of course, as the ink is used up the pressure within the barrel diminishes (there may also be some leakage) and the time finally comes when further flow of ink past the ball would result in reducing the pressure within the reservoir below atmospheric. Thereafter writing would be difficult, if not impossible. When this point is reached, or if at any time flow of the ink is arrested for any cause, the user can quickly cure the disability by unscrewing the plug 20 to the position shown in Figure 2 and screwing it in again. When the parts reach the position shown in Figure 2, the vent 12 permits air under atmospheric pressure to fill the cylinder and the reservoir so that when the plug is returned to writing position this new air is compressed and writing pressure restored.

As air can pass to the ink through the bore 9 of the plug 8, so ink might pass through the same bore in the reverse direction. If this should happen, this overflow would find itself within the chamber 10 of tube 1 between the two plugs 8 and

6. In order to leak, even into the barrel, this ink would have to traverse the bore 7 of the plug 6, the cylinder 11, and the vent 12. This is practically impossible, so that the chamber 10 may be considered as an adequate ink seal. In any event the ink reservoir is normally sealed by the cylinder 11. It is only when the compressor is being operated that the vent 12 is momentarily in communication with the ink reservoir, and it is only through this vent 12 that ink could possibly escape, and then only into the barrel. For all practical purposes, therefore, the pen is leakproof.

The relative sizes of the various parts of the pen which have been found satisfactory, are shown in the drawing, although, of course, these may be varied as well as structural details. I have found that the bores 7, 9 may satisfactorily be .018 inch in diameter.

Although I have shown and described an air compressor having a fixed piston and a movable

cylinder, the parts could be reversed, as they are in the first two of my above-recited copending applications.

I claim:

- 5 1. In a ball-pointed pen having a ball, an ink reservoir and a feed conduit connecting them, the combination of a cylinder slidably mounted upon and in communication with the reservoir, means for sliding the cylinder inward along the reservoir to compress the air within the reservoir and for holding it in air-compressing position, means for retracting it, a washer on the reservoir preventing substantial leakage of air between the reservoir and the cylinder wall, an air vent in the cylinder above the washer when the cylinder is in retracted position and below or opposite the washer during a substantial part of the compression stroke.
- 10 2. In a ball-pointed pen having a ball, an ink reservoir, and a feed conduit connecting them, the whole mounted within a barrel, the combination of a cylinder mounted upon and in communication with the reservoir, a screw plug threadedly mounted on the upper end of the barrel and movable within it, a spring pressing the upper end of the cylinder against the plug, whereby screwing the plug inward slides the cylinder over the reservoir and compresses the air within it, a washer on the reservoir preventing substantial leakage of air between the reservoir and the cylinder, an air vent in the cylinder wall above the washer when the plug is unscrewed to permit the spring to retract the cylinder, and below or opposite the washer during a substantial part of the compression stroke.
